REFRIGERATING APPARATUS

James J. Nance, Dayton, Ohio, assignor, by mesne assignments, to General Motors Corporation, a corporation of Delaware

Application August 14, 1930, Serial No. 475,179
Renewed July 11, 1934

14 Claims. (Cl. 62—4)

This invention relates to refrigerating systems and more particularly to the mechanism for controlling the temperatures produced by refrigerating systems.

In refrigerating systems it is customary to provide some means for maintaining the temperature within the evaporator or within the compartment which generally houses the evaporator, substantially constant. For instance, in compression systems, that is systems using a motor driven mechanical compressor or pump, this is generally accomplished by starting and stopping the motor, and consequently the compressor, at predetermined high and low temperature limits. In absorption machines, on the other hand, this is generally accomplished by starting and stopping the heating and cooling of the generator absorber, or the generator, at predetermined high and low temperature limits. In either case, the starting and stopping of the apparatus is generally accomplished by means of a snap switch responsive either to the temperature within the compartment to be cooled or to the temperature or pressure within the evaporator.

Frequently, however, it is desirable to provide means in conjunction with the refrigerating system for obtaining a temperature below that normally maintained in the evaporator or within the compartment to be cooled. For instance, in the freezing of water, sherbets, and the like, the freezing is more rapidly accomplished at a temperature below that normally necessary for maintaining food stuffs in a refrigerated condition. To this end, the so-called "Cold control" has been provided, consisting of means for temporarily changing the operation of the snap switch to produce a lower average temperature for a predetermined number of cycles of operation or periods of operation of the compressor, after which cycles the means functions automatically to reset the apparatus to its normal operation. A typical example of such a "Cold control" is shown in the patent to King, No. 1,658,342, February 7, 1928.

It has been found, however, in the use of a "Cold control" such as disclosed in the patent to King, that cycles of operation of the compressor frequency vary over wide ranges of time. For instance, one cycle of operation of the compressor may take a considerable length of time due to the necessity of removing a large amount of heat from the compartment to be cooled, while the next succeeding cycle of operation may be of very short duration if no more heat has been added to the compartment in the meantime.

Consequently, in the use of such a "Cold control" which is adjusted to maintain a lower than average temperature for a predetermined number of cycles or periods of operation of the compressor, it frequently happens that the apparatus operates under this reduced setting of the "Cold control" for a period of time much longer or much shorter than necessary to accomplish the results desired.

It is to apparatus for overcoming these objectionable features that my invention particularly relates, having for one of its objects apparatus or mechanism operating in conjunction with the refrigerating system for modifying the operation thereof or, in other words, to produce a lower temperature within the evaporator for a substantially definite period of time and independent of the number of cycles or periods of operation of the compressor or generator or generator-absorber.

Another object of the invention is to provide an improved control mechanism for a refrigerating system of the type in which the control mechanism is provided for maintaining a predetermined mean temperature in the cooling unit thereof, having means which can be actuated at will to modify the operation of the system temporarily to produce a different mean temperature of the cooling unit for a definite predetermined interval of time and to thereafter automatically restore the system to the normal control of the control mechanism.

A still further object of the invention is to provide an improved control mechanism for a refrigerating system of the type in which the control mechanism has means for maintaining the cooling unit of the system between predetermined temperature limits and to provide an auxiliary arrangement in the control mechanism which may be operated so as to give a considerable range of modifications of the temperature limits normally supplied by the control mechanism and to automatically restore the normal control of the mechanism from either of the positions which modify the temperature limits after a predetermined definite interval of time.

Further objects and advantages of the present invention will be apparent from the following description, reference being had to the accompanying drawings, wherein a preferred form of the present invention is clearly shown.

In the drawings:

Fig. 1 is a refrigerating circuit embodying the improved control device of the invention;

Fig. 2 is a front view of the improved control device;

Fig. 3 is a top view of the improved control device having the cover thereof removed and showing a portion of the control in section;

Fig. 4 is an enlarged view taken on the lines 5—4—4 of Fig. 3 showing a portion of the control in a position to modify operations of the refrigerating system;

Fig. 5 is an enlarged view taken on the lines 5—5 of Fig. 4 showing a stop member;

Fig. 6 is an enlarged view of a portion of the control device taken on the lines 6—6 of Fig. 8 showing a spring for automatically actuating the control into normal position;

Fig. 7 is an enlarged view of a portion of the control device taken on the lines 7—7 of Fig. 3 showing the connection of the time device with the control;

Fig. 8 is a view of a portion of the control device similar to Fig. 3 showing the control in a released position ready to be actuated into normal position;

Fig. 9 is a side view taken on the line 9—9 of Fig. 3 of a portion of the control device showing the switch contacts thereof in open position; and

Fig. 10 is a view similar to Fig. 9 of the control device showing the switch contacts thereof in closed position.

For the purpose of illustrating my invention I have shown a mechanical type of refrigerating apparatus which is represented diagrammatically by a circuit shown in Fig. 1, in which it is desired to maintain normally a predetermined temperature in a refrigerating element or evaporator. In the form of apparatus chosen for illustrating the preferred embodiment of the invention, the refrigerating element comprises an evaporator or cooling unit 10 to which a number of contacts 11 are attached in circulatory relation. Any suitable refrigerant, such as sulphur dioxide, is supplied to this element by means of a compressor 12 which forces the refrigerant into condenser 13 and thence into a receiver 14 from which it passes from pipe 15 through a float controlled valve, not shown, into the evaporator 10. The refrigerant, after boiling off in the evaporator 10 and coils 11 and performing its refrigerating effect in the well known manner, is circulated to the compressor through pipes 16 and 17. A suitable mechanism is provided for controlling the operation of the system, and, for the purpose of illustrating the invention, it is shown herein as a switch which is responsive to pressure conditions prevailing within the evaporator or cooling unit 10. This switch may have a flexible or expansible chamber 18, such as a metallic bellows, the movement of which, in response to the pressure variations in the system, causes the making and breaking of an electric circuit at the point 19 so as to start and stop the motor 20 which is used for driving the compressor.

In the control mechanism, the bellows 18 is contained within a mounting guard 21 and has its upper end 22 secured to a lever 23 which is pivoted at 24. The opposite end of lever 23 extends into a bracket 25 and has a lever 26 pivoted thereto by a stud 27. The lever 26 has a cam mounted at one end thereof engaging a spring pressed roller 29 which provides a snap action mechanism for quickly moving an electric contact 30 into or out of engagement with a similar contact 30a located therebelow. The lever 23 therefore serves as a means for moving the electrical contact 30 upwardly with respect to the contact 30a in response to movement of the pressure responsive element or bellows 18. The

contact 30 is secured to an arm 31 pivoted at 32 and having its other end attached to the lever 26 by an insulating link 33. A stud 34 passes through the lever 26 and through the link 33 to hold these parts together and extends upwardly 5 a great distance from the lever. The bellows, levers, and other parts are all mounted upon a base 35 to which a threaded stud 36 extends and has springs therearound which abut the base 35 and provide adjustment for the control device. Under normal operating conditions the bellows 18 is adapted to be expanded or contracted 10 in response to pressures within the system for actuating the lever 23 up and down. This movement causes the cam 28 secured to the lever 26 15 to force the spring pressed roller 29 upwardly, thus permitting the cam to travel to the opposite side of the roller. When this movement occurs a snap action is imparted to the lever 26 which causes the movable contact 30 to quickly engage 20 or disengage its operating stationary contact. In this manner the motor of the system is started and stopped to cause the compressor to cyclically withdraw refrigerant from the evaporator. The foregoing mentioned parts of the control device 25 are identical to and operate in the same manner as the control device shown in the patent to Otto M. Summers, No. 1,819,979, issued August 18, 1931.

The apparatus is usually adjusted at the factory or in the field by a serviceman for such normal operation by suitably tensioning the springs which surround the stud 36 and in such condition the lever 23 will have its upward and downward movements resisted so that it will open or close 35 the circuit of the driving motor 20 only at the maximum and minimum pressure-temperature points for which the tension corresponds.

It is desirable to provide means whereby the control device can be temporarily modified to 40 cause the system to produce a lower temperature in the evaporator thereof than is afforded by the normal adjustment made at the factory or by the serviceman in the field. This can be accomplished by interposing a resistance to the downward movement of the lever 23, the operation of the switch contacts thus being delayed so that the system will continue operating for a longer period of time, thereby prolonging the freezing cycle of the system. Likewise, if the resistance 45 to the downward movement of the lever 23 is increased it will require a greater effort on the part of the diaphragm or bellows 18 to pull the lever down into contact breaking position (the descent of lever 23 causing the raising of contact 30 away from its corresponding stationary contact 30a, thus breaking the circuit).

A suitable method of interposing such a resistance is illustrated in the embodiment of the present invention and consists in placing a resilient obstruction in the path of the downwardly moving lever 23. A spring 37 is used for this purpose and in the preferred embodiment of the invention the spring 37 is coiled and hooked into and carried by a slotted shaft 38 so 60 arranged that one end 39 of the spring 37 projects while the body of spring 37 is forced to rotate with the shaft 38 when same is turned. The pin or stud 27 extends outwardly from lever 23 and is engaged by the spring 37 in such a 65 manner that when the lever 23 descends, the pin 27 engaging the spring leg 39 will have its downward movement resisted to an extent corresponding to the degree to which the spring 37 is wound.

The spring 37 carried by the shaft 38 may be 75

rotated and wound up so that a correspondingly greater tension is caused to bear against the downward movement of lever 23. Thus, if the spring is wound in the position indicated by the arrow beneath the "Colder" as shown in Fig. 2 more and more tension may be exerted against the descent of the lever 23. Various degrees of tension may be secured, ranging from a maximum to a minimum and while any intermediate point between these extremities may be selected as a position at which to station the spring or wind the spring, in a device suitable for manipulation, it is preferable to have a selected series of stations to which the spring may be wound. Thus, as shown in Fig. 2, the front 41 of casing 42 is provided with a dial 43 having points represented by numbers at which the spring may be stopped in its rotation or winding. The shaft 38 which carries the spring 37 is rotated in turn by an operating handle or knob 44 secured to a shaft 45 and held in any position by a spring 46 compressed between the wall 41 of casing 42 and a plate 47 when the knob 44 is released and pushed inwardly. The plate 47 is secured to the shaft 45 so that it will rotate therewith and is provided with an extension having a button 48 secured thereto. The button 48 is adapted to be forced into any of the holes 49 provided in plate 51 which is mounted on the bottom of casing 42 by screws 52. It is to be understood that the holes 49 are located in alignment with the points designated by the numerals on the dial 43.

The resilient modifying device just described is so arranged that, when the knob or handle 44 is pulled out and turned to cause the leg 39 of spring 37 to be in the path of the downward movement of lever 23, a maximum resistance is interposed to the descent of the lever 23. This position is shown in Fig. 3 where the spring carrying shaft handle or knob 44 is in the number 6 operating position. It is evident that an appreciable drag is presented to the lever 23. The result of this retardation of the downward movement of lever 23 will be to cause the prolongation of the freezing cycle, in other words, a longer-than-normal operation of the compressor.

It is evident that the duration of this longer-than-normal operation of the compressor will be decreased as the spring is further untensioned, that is, as the spring-carrying shaft and handle 44 is moved to successive positions in the clockwise direction opposite that indicated by the arrow beneath the word "Colder" in Fig. 2.

After the refrigerator has been in operation for an appreciable period, a considerable amount of frost will collect around the coils and act substantially as an insulator.

In order to defrost the refrigerating element, it is necessary to shut down the operation or discontinue the operation of the compressor and this is effected by completely blocking the movement of the control mechanism as by interposing an obstruction to the downward movement of the lever 26. For this purpose a blocking arm 54 is rigidly mounted on the spring carrying arrangement shown in Fig. 3. This arm 54 is normally entirely out of the path of the pin extending from arm 26 and is therefore ineffective while the refrigerating system is in operation and while the resilient modifying device is in any of its effective positions. By pulling out handle 44 a greater distance than is ordinarily required to move the plate 47, the button 48 will then clear the stop pin 58a, stationarily mounted on plate 51, and the handle 44 can then be moved in an oppo-

site direction to the arrow shown in Fig. 2 to the position marked "Defrost" as shown in Fig. 2 so as to engage the underside of the pin 34. The apparatus will continue to defrost since the arm 54 arrests the downward movement of arm 26 by its engagement with the pin 34 extending from this arm 26. This position of arm 54 is not disclosed in the drawings. However, this position can be clearly understood since the arm 54 is rigidly mounted on the shaft 38 and is rotated with this shaft and with the spring-carrying arrangement shown in Fig. 3. Fig. 3 of the drawings shows the arm 54 above the pin 34 but it must be remembered that leg 39 of spring 37 moves in a counter-clockwise direction in advance of arms 54 and engages the pin 27 when the knob 44 is set into any of the positions to cause longer than normal operation of the compressor, hence as shown in Fig. 3 the knob is in No. 6 position and of course the arm 54 is disposed in a plane above the pin 34 but does not engage the pin.

The dotted lines in Fig. 4 show the plate 47 and button 48 in number 1, or normal, position of the switch and corresponds to Fig. 2 except that it is a cross section immediately behind the front wall 41 of casing 42. The full line position in Fig. 4 shows the switch in its "Colder", or number 6, position, and corresponds to Fig. 3.

The following described parts and their operation can be constructed in any suitable manner to perform the desired results without departing from the invention which I am about to describe. For instance, these parts may all be constructed substantially similar to the construction shown in the Summers patent heretofore referred to but assembled in a different manner.

Manufacturers of refrigerating apparatus have experimented with and determined approximately the length of time required to freeze at a certain predetermined temperature such substances as water, ice cream, sherbets, and the like and are at present publishing booklets containing various recipes for concocting such substances, together with instructions for placing and leaving the arm or pointer of the so-called "Cold control" in certain positions to modify the operations of the apparatus to produce a lower temperature before manually returning the pointer to normal position. The user of a "Cold control" of this type is always confronted with such hazards, for example, as that of freezing everything contained in the cooling compartment of the refrigerator due to the low temperature produced by the evaporator which will occur should they forget to return the pointer of the device back to normal position.

It is therefore an object of this invention to provide means for eliminating such hazards in refrigerating apparatus and I have provided means whereby the apparatus heretofore described can be combined with a mechanism for automatically returning the handle or knob 44 and the parts connected therewith for modifying the control device to normal position or to the position designated by the numeral 1 on the dial 43 shown in Fig. 2. To this end I provide a member 56 extending through an opening in the rear wall of casing 42 and into which the shafts 38 and 45 extend and are connected together by a sliding connection 57. The member 56 is provided with a pin 58 and is held in a certain position by the screw 59 which passes through the wall of casing 42. Member 56 is provided with a camming surface 61 which is engaged by the roll-

er 62. Roller 62 is secured to one end of a yoke 63 which surrounds the shaft 45 and has its opposite end 64 connected, by a pin 65, mounted near the outer circumference of a wheel 66. Wheel 66 is journaled on a shaft of a clock or chronometric timing device, the mechanism of which is not shown. The chronometric timing device may be an ordinary alarm clock or the like which has a spring wound alarm mechanism adapted to be released at a certain predetermined time to cause rotation of the wheel 66. The roller 62 also engages a circular plate 71 loosely mounted upon the shaft 45 and adapted to abut a shoulder 72 provided on shaft 45. A coiled spring 73 surrounds the shaft 45 and has one end thereof secured to the shaft 45 and has its other end secured to a pin 74 mounted on plate 51. This spring 73 is wound to a predetermined tension and is arranged to resist the movement of the handle or knob 44, in the direction shown by the arrow beneath "Colder" in Fig. 2, before it has its ends permanently secured. Thus, the arrangement of spring 73 provides a means for rotating the shaft 45 and knob 44 when the timing device releases to cause movement of roller 62.

The timing device, which may be an alarm clock, is secured to and within the casing 42 by a face 76 having the usual hour and minute hands or pointers cooperating with numerals for designating time. There is also a second series of numerals on the face 76 having a hand or pointer cooperating therewith for designating the time at which the alarm mechanism may be set to release. A stem 77 may be utilized for moving the hour and minute hands or pointers of the time device. Another stem 78 may be utilized for moving the hand or pointer to any desired position of the second series of numerals to indicate the time at which the alarm should release. The key 79 may be employed for winding the time device. Another key 80 may be utilized for winding the alarm mechanism. The time device mechanism and other parts associated therewith are all contained within the casing 42, which casing is secured to the base 35 of the control by brackets 81 and screws 82.

In order to protect the control, a sheet metal cover 83, see Fig. 2, is provided. This cover has openings or slots in its side wall, (not shown), to provide means whereby the cover may be placed on the control without striking the brackets 81 and the member 56. Suitable locking means or retaining means include the catches 84 secured to springs 85, which springs are in turn fastened to studs 86 mounted on the base 35. Catches 84 have an outwardly extending member or hook which enters an opening in the cover 83 and removably secures the cover on the base. In this manner it is evident that the control device may be inspected and, if necessary, adjusted without dismantling the same.

Having thus described various elements of my improved apparatus, the operation of the mechanism to automatically restore the auxiliary adjustment device to normal position, or position indicated by the numeral 1 on dial 43, will now be explained. In order to set the device to any position to resist the downward movement of lever 23 or to modify the pressures at which the control is adapted to be actuated, the knob or handle 44 may be pulled out sufficiently to remove the button 48 on plate 47 from the opening or hole 49 located in plate 51. The knob 44, shaft 45, plate 47, and spring 37 can be rotated in a coun-

terclockwise direction into any of the positions for causing longer than normal operations of the compressors. After the plate 47 has been moved into any of the positions indicated on the dial 43 this plate 47 can also be moved back in a clockwise direction to any of the other positions designated by the numerals, of less value, on dial 43, that is from number 6 position in Fig. 3 to any of the positions indicated on dial 43 if desired. During this movement the spring 46 will be compressed and will apply sufficient tension upon the shaft 45 to cause the shaft 45, knob 44, and end plate 47 to move inwardly when released. It is therefore apparent that the knob 44 can be manually moved back from position No. 6 to any of the other positions indicated on the dial 43 (see Fig. 2) after the device has been set without hindering the operation of the mechanism, for automatically restoring the auxiliary adjustment device to normal position. Thus, the spring 46 holds the button 48 in engagement with any of the holes 49, located in plate 51, at which the knob is set to permit spring 37 to be placed in the downward path of lever 23 thereby increasing the spring tension which the lever 23 must overcome before actuating the electric contact 30 to interrupt the electric circuit to the motor 20. In this manner the motor 20 will be caused to actuate the compressor 12 a longer period of time than ordinarily required to produce a lower temperature in the evaporator. It is to be understood that the sliding connection 57 of shafts 38 and 45 permit the knob 44 and shaft 45 to be pulled outwardly without moving shaft 38 and parts mounted thereon. The wheel 66 will be automatically returned to a position rendering it capable of moving the yoke 63 and roller 62 sideways, or to the left as viewed in Fig. 3, by engagement of roller 62 with plate 71, which plate will be forced inwardly by the spring 46 when the device is set in any of the positions indicated on the dial 43 other than "No. 1" and "Defrost". The alarm mechanism may be arranged so that the wheel 66 will rotate only sufficiently to move roller 62 until it strikes the stop pin 58. Thus, the roller remains on the camming surface 61 of member 56 so that it will be in position to always be reset or forced to the bottom of the camming surface when the device is actuated into any of the positions except normal operating position. After the device has been actuated into any of the various positions, to cause the compressor to operate longer, the device may then be set to automatically return it to normal position to restore the refrigerating system to normal operation after a predetermined interval of time regardless of the number of cycles the apparatus makes during such predetermined time. In order to accomplish the automatic return of the device to normal position the stem 78 is actuated to set the alarm mechanism so that it will release after a definite predetermined interval of time. This can be indicated by the small pointer on the face 76 of the clock, together with pointers indicating hours and minutes of time. The key 80 is then actuated to wind the alarm mechanism to insure its operation at the time for which it has been set to operate the release. When the desired interval of time has elapsed the alarm mechanism will release causing the wheel 66 to rotate. Rotation of wheel 66 causes the yoke 63 carrying roller 62 to move sideways and the roller moves upwardly on the camming surface 61 of member 56. Engagement of the roller 62 with plate 71 which

abuts the shoulder 72 on shaft 45 causes shaft 45 to move outwardly, thus disengaging the button 48 from hole 49. This position of the device is clearly shown in Fig. 8 of the drawings. At 5 this moment spring 73, being under a predetermined tension, causes rotation of the shaft 45 in a clockwise direction. Shaft 45 will rotate in this direction until the pointer on knob 44 reaches normal position or until the extension of plate 47 which carries button 48 comes into engagement with stop pin 56a, see Fig. 4. The wheel 66 is adapted to remain in its released position until the device is reset, therefore the roller 62 prevents the button 48 from entering any of the 10 openings 49 during rotation of plate 47. Rotation of shaft 45 will thereby be stopped by its engagement with pin 56a and the spring 46 will then force button 48 into the opening or hole 49 in plate 51 directly opposite normal position. Rotation of wheel 66, which rotation is caused by movement of yoke 63, in a direction to the right as viewed in Fig. 3 of the drawings, when the roller 62 is set into its position to release button 48 at a certain time, will tend to turn the alarm 15 mechanism of the timing device. It is therefore desirable to provide means on the shaft of wheel 66 which will permit wheel 66 to be rotated in one direction without disturbing or rotating the alarm mechanism of the timing device such 20 as when the apparatus is being set into any of the colder positions. Such a means can be in the form of a ratchet arrangement connected to the shaft upon which the wheel 66 is mounted so that rotation of the wheel 66 by the alarm mechanism in one direction will move the yoke 63 and roller 62 while movement of the yoke 63 in an opposite direction will not disturb or rotate the alarm mechanism of the time device. Ratchet arrangements of the type described are well-known in their respective art and it is believed 25 to be unnecessary to illustrate how such a conventional arrangement can be applied to the apparatus disclosed. It is to be understood that instead of using an alarm clock mechanism, a device which could be set for a predetermined interval of time other than an alarm clock mechanism could be employed in the invention.

It is therefore apparent from the foregoing description that I have provided an improved control device for refrigerating system, operation of which can be modified for a predetermined definite interval of time and thereafter automatically restored to normal operating condition. Furthermore, I have provided an improved switch 50 which is a unitary structure adapted to be installed as a unit in a mechanical refrigerator and having provisions for temporarily changing the temperature of the evaporator located in the refrigerator and also provided with means for defrosting said evaporator at will.

While the several forms of embodiment of the invention as herein disclosed, constitute a preferred form, it is to be understood that other forms might be adopted, all coming within the 55 scope of the claims which follow.

What is claimed is as follows:

1. A refrigerating system comprising in combination, a cooling element, means for circulating a refrigerating medium through said element, means for maintaining said element at a normal predetermined average temperature, manually actuatable means for temporarily modifying said second named means to obtain a temperature of said cooling element different 70 from the normal average temperature thereof,

and chronometrically operated means cooperating with said manually actuatable means and controlling the duration of effectiveness thereof, said chronometrically operated means being operable independently of said first and said second named means for automatically restoring the system to normal operation. 75

2. A refrigerating system comprising in combination, an evaporator, means for withdrawing gaseous refrigerant from the evaporator to condense the same and to circulate the condensed refrigerant to the evaporator, and apparatus for controlling said means including mechanism for obtaining normally a certain average temperature of the evaporator, said apparatus including a selective setting device for selectively obtaining a plurality of different average temperatures of the evaporator, said apparatus also including chronometrically operated means cooperating with said setting device and controlling the duration of effectiveness thereof, said chronometrically operated means being operable independently of said first named means and said controlling apparatus for automatically restoring said mechanism to normal operating condition. 10 15 20 25

3. A refrigerating system comprising in combination, an evaporator, means for withdrawing gaseous refrigerant from the evaporator to condense the same and to circulate the condensed refrigerant to the evaporator, and apparatus including mechanism for cyclically starting and stopping said means automatically in response to certain high and low temperatures respectively of the evaporator, a selective device for temporarily modifying the operation of said mechanism to secure the starting of the cycles at a plurality of selective lower degrees of temperature than normally required, said apparatus including chronometrically operated means co- 30 35 40 operating with said device and controlling the duration of effectiveness thereof, said chronometrically operated means being operable independently of said first named means and said apparatus for automatically restoring said mechanism to normal operating condition, and said chronometrically operated means including means adapted to be adjusted for varying the time of modified cycles. 45

4. A refrigerating system comprising in combination, a cooling unit, means for cyclically circulating a refrigerant medium through said unit, control apparatus for controlling the circulating cycles of said means whereby to cool said unit to a predetermined average temperature, a selective device for temporarily modifying the cycles of operation of said means whereby to obtain a plurality of selective different average temperatures in said unit, chronometrically operated means associated with said modifying device for controlling the duration of effectiveness thereof, said chronometrically operated means being operable independently of said first named means and said control apparatus for automatically restoring the system to normal operating condition. 50 55 60 65

5. A refrigerating system comprising in combination, a cooling unit, means for withdrawing refrigerant from the cooling unit for condensing the refrigerant and for delivering it again to the cooling unit, an apparatus for controlling said 70 means including a pressure responsive element, electric contacts, snap action mechanism for said contacts, manual operating means normally independent of said snap action mechanism but operable to modify said snap action mechanism 75

to vary the pressure at which said mechanism is responsive without disturbing the normal adjustment of said apparatus, and chronometrically controlled means cooperating with said manual 5 operating means and operable independently of said first named means and said apparatus for automatically actuating said manual means out of engagement with said snap action mechanism after said manual means has been in engagement 10 with said snap action mechanism for a predetermined period of time.

6. A refrigerating system comprising in combination, a cooling unit, means for withdrawing refrigerant from the cooling unit for condensing 15 the refrigerant and for delivering it again to the cooling unit, an apparatus for controlling said means including a pressure responsive element, electric contacts, snap action mechanism for said contacts, manual operating means normally independent of said snap action mechanism but operable to modify said snap action mechanism to vary the pressure at which said mechanism is responsive without disturbing the normal adjustment of said apparatus, chronometrically controlled means cooperating with said manual operating means and operable independently of said first named means and said apparatus for automatically actuating said manual means out of engagement with said snap action 25 mechanism after said manual means has been in engagement with said snap action mechanism for a predetermined period of time, and said chronometrically controlled means including means for varying the time of effectiveness of said 30 manual operating means.

7. Refrigerating apparatus including a refrigerant liquefying means and a refrigerant evaporating means, control means for controlling the operation of the apparatus for providing a normal refrigerating temperature, said control 40 means including selective means for providing lower than normal refrigerating temperatures and selective means for providing higher than normal refrigerating temperatures, one of said 45 selective means being automatically operative to return the apparatus to normal refrigerating temperatures.

8. Refrigerating apparatus including a refrigerant liquefying means and a refrigerant evaporating means, control means for controlling the operation of the apparatus for providing a normal refrigerating temperature, said control means including selective means for providing lower than normal refrigerating temperatures 55 and selective means for providing higher than normal refrigerating temperatures, one of said selective means including means for retaining it in modified position to provide a modified temperature and thereafter returning it to normal position to again provide normal refrigerating 60 temperatures.

9. Refrigerating apparatus including an evaporator, means for circulating a refrigerant through said evaporator, control means for controlling said circulating means, said control means having a normal action operation to control said circulating means to maintain a normal refrigerating temperature in said evaporator, means associated with said control means for varying the 65 normal control action of said control means to

provide a lower than normal temperature in said evaporator, means associated with said control means for varying the normal control action of said control means to produce a higher than normal temperature in the evaporator, one of said means associated with the control means being rendered inoperative after performing its function to thereby permit the control means to automatically return to its normal control action. 5

10. Refrigerating apparatus including a refrigerant liquefying means and a refrigerant evaporating means, control means for controlling the operation of the apparatus for providing normal ice freezing temperatures whereby frost accumulates upon the evaporating means, said control 15 means including selective means for providing lower than normal freezing temperatures and selective means for providing temperatures above ice freezing temperatures to melt frost from the evaporating means, one of said selective means 20 being automatically operative to return the apparatus to normal ice freezing temperatures.

11. Refrigerating apparatus including a refrigerant liquefying means and a refrigerant evaporating means, control means for controlling the operation of the apparatus for providing a normal refrigerating temperature, said control means including selective means for providing lower than normal refrigerating temperatures and selective means for providing higher 30 than normal refrigerating temperatures, one of said selective means being rendered inoperative automatically after a predetermined time to return the apparatus to normal refrigerating temperatures. 35

12. Refrigerating apparatus including a refrigerant liquefying means and a refrigerant evaporating means, control means for controlling the operation of the apparatus for providing normal ice freezing temperatures whereby frost accumulates upon the evaporating means, said control means including selective means for providing lower than normal freezing temperatures and selective means for providing temperatures above ice freezing temperatures to melt the frost from the evaporating means, one of said selective means being rendered inoperative automatically whereby to return the apparatus to normal ice freezing temperatures. 40

13. Refrigerating apparatus including refrigerant liquefying and evaporating means, control means for controlling the operation of the apparatus to provide a normal refrigerating temperature, said control means including chronometrically controlled means for varying the refrigerating temperature, said chronometrically controlled means including selective means for providing different temperature variations from the normal refrigerating temperature. 50

14. Refrigerating apparatus including refrigerant liquefying and evaporating means, control means for controlling the operation of the apparatus to provide a normal refrigerating temperature, said control means including means for providing lower than normal refrigerating temperatures and means for providing higher than normal refrigerating temperatures, and chronometric means for controlling one of said two last mentioned means. 65
